DESIGN FOR A HANDLE FOR A VACUUM CLEANER OR SIMILAR ARTICLE

Lurelle Guild, Darien, Conn., assignor, by mesne
assignments, to Electrolux Corporation, Dover,
Del., a corporation of Delaware

Original application March 25, 1937, Serial No.
D-68,404. Divided and this application of Sep-
tember 8, 1937, Serial No. D-71,509

Term of patent 14 years

To all whom it may concern:

Be it known that I, Lurelle Guild, a citizen of
the United States of America, residing in Darien,
Connecticut, have invented a new, original, and
ornamental Design for a Handle for a Vacuum
Cleaner or Similar Article, of which the following
is a specification, reference being had to the
accompanying drawing, forming part thereof.

This application is a division of my co-pending
application Serial No. D-68,404, filed March 25,
1937.

Fig. 1 is a plane view of the handle, showing
my new design.

Fig. 2 is a side view of the handle.

Fig. 3 is an end view of the handle.

Fig. 4 is a sectional view of the handle, along
line 4—4 of Fig. 2, and Fig. 5 is a perspective
view of the handle.

I claim:

The ornamental design for a handle for a
vacuum cleaner or similar article, as shown.

LURELLE GUILD.
